US00D949695S

(12) **United States Design Patent** (10) **Patent No.:** **US D949,695 S**
Borrero et al. (45) **Date of Patent:** **** Apr. 26, 2022**

(54) **PACKAGE**

- (71) **Applicant:** **The Procter & Gamble Company**,
Cincinnati, OH (US)
- (72) **Inventors:** **Susana E Borrero**, Mason, OH (US);
Benjamin G Hesford, Hamilton, OH (US);
Jun You, West Chester, OH (US);
Stephen Michael Truesdell, Liberty Township, OH (US)
- (73) **Assignee:** **The Procter & Gamble Company**,
Cincinnati, OH (US)

(**) **Term:** **15 Years**

(21) **Appl. No.:** **29/711,290**

(22) **Filed:** **Oct. 30, 2019**

(57) **CLAIM**

The ornamental design for a package, as shown and described.

DESCRIPTION

FIG. 1 is a perspective view of a package;
FIG. 2 is a front view of the package;
FIG. 3 is a right side view of the package;
FIG. 4 is a back view of the package;
FIG. 5 is a left side view of the package;
FIG. 6 is a top view of the package; and,
FIG. 7 is a bottom view of the package.

The dash-dot-dash broken lines depict the boundaries of the claim. All other broken lines depict portions of the package that form no part of the claimed design.

1 Claim, 4 Drawing Sheets
